[57] **CLAIM**

The ornamental design for a booth, as shown and described.

DESCRIPTION

FIG. 1 is a perspective view of a booth showing my new design, taken from the front and from below;

FIG. 2 is a perspective view of FIG. 1, taken from behind and from above;

FIG. 3 is a top plan view of FIG. 1;

FIG. 4 is a bottom plan view of FIG. 1;

FIG. 5 is a perspective view of a second embodiment of the design of FIG. 1, the only difference being in the length of the side panels;

FIG. 6 is a perspective view of a third embodiment of the design of FIG. 1, the only difference being the length of the side panels;

FIG. 7 is a perspective view of a fourth embodiment of the design of FIG. 1, the only difference being the length of the side panels.

FIG. 1
